UNITED STATES PATENT OFFICE

LUDWIG ROEBEL, OF MANNHEIM, GERMANY, ASSIGNOR TO AKTIENGESELLSCHAFT BROWN, BOVERI & CIE, OF BADEN, SWITZERLAND, A JOINT-STOCK COMPANY OF SWITZERLAND

CIRCUIT-BREAKING APPARATUS

Application filed March 9, 1928, Serial No. 260,408, and in Germany March 12, 1927.

This invention relates to improvements in circuit-breaking apparatus.

The opening of so-called high-speed circuit breakers constructed heretofore occurs through the action of a spring which acts either directly on the movable breaker contact or acts to release the breaker through a suitable latching device. The opening time proper of these high-speed breakers is very short, but the total time elapsing from the beginning of the short-circuit until the end of the interruption is still relatively long due to the relatively large moment of inertia of the masses to be moved in opening the breaker and the correspondingly longer period of time necessary to accelerate such masses.

One of the objects of the present invention, therefore, is to provide improved circuit-breaking apparatus wherein the total time elapsing from the beginning of the short-circuit until the end of the interruption is appreciably smaller as compared with such time elapsing in the interrupting or circuit-breaking action of such apparatus constructed heretofore.

Other objects and advantages will hereinafter appear.

For the purpose of illustrating the invention, several embodiments thereof are shown in the drawings, wherein

Figure 1 is a diagrammatic side elevational view; and

Figs. 2 to 4 are similar views, illustrating modified arrangements.

In the embodiment of the improved apparatus shown in Fig. 1, the circuit-breaking means, designated generally by the reference numeral 10, controls the line 11 and is held in closed position by suitable spring means 12. For the purpose of effecting opening movement or circuit-breaking action of breaker 10, the same is connected through the rod 13, pivotally connected at 14, to the segment 15 loosely mounted on the shaft 16 to which is fixed the motive means 17 which may be in the form of a fly wheel rotating constantly, in the direction indicated and at substantially uniform speed, under the driving action of some suitable power means such as a motor (not shown). Disposed about the motive ele-

ment or fly wheel 17 is the friction band 18 secured, as shown, at its ends to the armature 19 of the magnet 20 fixed to and carried by segment 15 and provided with the energizing coil or winding 21. With the parts in the position shown, with armature 19 held under the action of the tension spring 22 against the stop 23 fixed in segment 15, the friction band 18 is released from operative frictional engagement with fly wheel 17.

Upon occurrence of overload or short-circuit condition in line 11, winding 21 is excited through the transformer 24 to cause clockwise movement of armature 19 against the action of spring 22, whereupon band 18 grips fly wheel 17 to connect or couple segment 15 to the same for rotary movement therewith, the kinetic energy of the fly wheel being such as to effect substantially instantaneous opening movement of breaker 10 against the action of its holding spring 12. Suitable latching means 25 is provided to hold breaker 10 in open position, the latching means being arranged to engage the dog or detent 26 before band 18 is released by such amount as would permit the breaker to close again under the action of spring 12, it being noted in this connection that as soon as the breaker opens, the connecting transformer 24 becomes deenergized.

Suitable brushes 27 maintain connection between winding 21 and transformer 24 while permitting of such counter-clockwise movement of segment 15 as is necessary to effect full opening movement of breaker 10.

In the embodiment shown in Fig. 2, the arrangement is just the opposite to that in Fig. 1, in that the winding 21' is normally energized and is deenergized upon overload or short-circuit condition in line 11' to permit the tension spring 22' to impart clockwise movement to the armature 19', whereupon the friction band 18' is tightened or applied to provide an operative coupling or connection between fly wheel 17' and segment 15', at which time the breaker 10' is opened and held in open position by the latching means 25'. Before the breaker reaches its full open position, the coupling band 18' is released by counter-clockwise movement of armature 19'.

to its initial position due to engagement of the lower end of the armature with a suitable fixed stop 28 supported independently of the fly wheel and segment 15'.

5 The coil 21' is normally excited through the transformer 24'. Upon occurrence of an overload or short-circuit condition in line 11', the relay 29 operates to open the exciting circuit for coil 21', whereupon the apparatus 10 functions as explained above. In Fig. 2 the various parts have been given primed designating characters corresponding to those designating corresponding parts in Fig. 1.

In the embodiment shown in Fig. 3, an 15 electromagnetic clutch is used in lieu of the friction coupling band in Figs. 1 and 2. The clutch comprises the magnet 30 disposed for radial movement between suitable guides 31 with which the segment 15'' is provided, and 20 the operating winding 32. The construction and arrangement are otherwise as shown in Fig. 1. Upon excitation of winding 32 at overload or short-circuit condition, an electromagnetic coupling with the fly wheel 17'' 25 is established, the latter acting as an armature. Simultaneously with this action, magnet 30 moves radially inwardly into frictional engagement with the periphery of the fly wheel, thereby providing a better operating 30 connection with the same. Tension springs 33 operate normally to hold magnet 30 in its outermost position out of engagement with the periphery of the fly wheel.

In the embodiment shown in Fig. 4, the 35 fly wheel is provided with the conductors 34. The electromagnetic clutch comprises the magnet 30' fixed to and carried by the segment 15''' and the operating winding 32'. The construction and arrangement is otherwise the same as in Fig. 3. Upon occurrence 40 of overload or short-circuit condition, the eddy currents produced by the fly wheel establish the coupling between the same and magnet 30' to cause counter-clockwise movement of segment 15''' with the fly wheel and 45 consequent opening of the breaker. In Fig. 4 a holding coil 35, normally energized through the local circuit shown, is substituted for the spring 12 in Fig. 1. A suitable relay 36, connected in series with the operating circuit for winding 32', operates upon occurrence of overload or short-circuit condition in the line to open the local circuit for holding coil 35 to permit of more ready opening of the breaker by the kinetic energy stored in the fly wheel. Suitable latching means 37 may be provided to hold relay 36 in open position when the breaker is open. 50 From the foregoing, it will be seen that improved circuit-breaking apparatus has been provided wherein the breaker is opened within a substantially shorter period of time than has been possible in such apparatus constructed heretofore, and that the moment of

inertia of the movable parts has been entirely compensated for.

Various changes in the size, shape and arrangement of the parts may be adopted without departing from the spirit of the invention or the scope of the claims. 70

The invention claimed is:

1. In electrical circuit control apparatus comprising a circuit breaker, constantly-operating motive means for actuating said circuit breaker, and means responsive to a predetermined condition of the electrical circuit and operable upon occurrence of such condition to effect mechanical connection between said circuit breaker and said motive 75 means.

2. In electrical circuit control apparatus comprising a circuit breaker, constantly-operating motive means for effecting actuation of said circuit breaker, means for mechanically coupling said motive means with said circuit breaker, and means responsive to a predetermined circuit condition and operable upon occurrence of such circuit condition 85 to actuate said coupling means to operatively 90 connect said motive means with said circuit breaker.

3. In electrical circuit control apparatus comprising a circuit breaker, actuating means therefor, a constantly-operating motive means for actuating said actuating means, means for frictionally engaging said actuating means with said motive means, and means operative upon a predetermined circuit 95 condition to actuate said frictional engaging means to mechanically connect said motive means with said actuating means to 100 actuate said circuit breaker.

4. In electrical circuit control apparatus comprising a circuit breaker, actuating means therefor, a constantly-operating motive means for effecting actuation of said actuating means, electromagnetic means for coupling said actuating means to said motive 105 means, and means responsive to a predetermined circuit condition and operable upon occurrence of such condition to effect actuation of said electromagnetic means to magnetically connect said actuating means with 110 said motive means to effect actuation of said circuit breaker directly by said actuating means.

5. In electrical circuit control apparatus comprising a circuit breaker, constantly-operating motive means for actuating said circuit breaker, means automatically operative responsive to a predetermined circuit condition to effect mechanical connection of the said actuating means with said motive means to effect actuation of said circuit breaker. 115

6. In electrical circuit control apparatus comprising a circuit breaker, actuating means therefor, constantly-operating motive means, means automatically operative responsive to a predetermined circuit condition 120

to render said motive means effective to operate said actuating means to effect direct actuation of said circuit breaker by said actuating means, and means operative to maintain said circuit breaker in such actuated position.

In testimony whereof I have hereunto subscribed my name this 24th day of February A. D. 1928.
